United States Patent Office

Des. 181,306
Patented Oct. 29, 1957

181,306

DINNER PLATE OR SIMILAR ARTICLE

Charles H. McKaig, Camillus N. Y., assignor to Onondaga Pottery Company, Syracuse, N. Y., a corporation of New York

Application March 1, 1957, Serial No. 45,042

Term of patent 14 years

(Cl. D44—15)

The drawing is a plan view of a plate of conventional configuration, showing my new design.

I claim:

The ornamental design for a dinner plate or similar article, as shown and described.
